UNITED STATES PATENT OFFICE.

CHARLES F. ADAMS, OF SWAMPSMOTT, MASSACHUSETTS, ASSIGNOR TO HAMEL SHOE MACHINERY COMPANY, A CORPORATION OF MASSACHUSETTS.

LASTING MACHINE.

1,412,032.

Specification of Letters Patent. Patented Apr. 11, 1922.

Application filed October 29, 1919, Serial No. 334,269. Renewed September 15, 1921. Serial No. 500,969.

To all whom it may concern:

Be it known that I, CHARLES F. ADAMS, a citizen of the United States, residing at Swampscott, in the county of Essex and State of Massachusetts, have invented certain new and useful Improvements in Lasting Machines, of which the following is a specification, reference being had therein to the accompanying drawings.

10 This invention relates to lasting machines and specifically to that type employed for end lasting and commonly known as "bed lasters". In machines of this character a pair of substantially flat and relatively movable plates termed "wipers" are usually employed for smoothing and fitting the upper leather about the toe or heel and for forcing it closely down upon the bottom of the innersole. For operating upon shoes

15 having different end contours, as for example the toes of right and left shoes of a pair, it is necessary to use wiper plates of different shapes and it thus becomes desirable to provide means whereby such plates may be removably secured in the machine.

20 The present invention, therefore, provides securing means for the wiper plates which permits of their ready removal and replacement with a minimum of time and effort on

25 the part of the operator.

The invention further consists in the employment of securing means for the wiper plates comprising a slidable retaining member and an arrangement of parts such that

30 the retaining member when in normal position is locked against sliding movement but may by slight manual operation be unlocked to permit it to slide freely.

The invention contemplates as a further

35 desirable feature the employment of a common pivotal connection for the wipers of a pair, such connection comprising a stud projecting outwardly beyond the surface of one or both of the wipers and adapted to have such projecting portion or portions of

40 said stud removably held in engagement with a suitable support whereby the wipers may be properly positioned in the machine.

45 Other and further objects and advantages

50 of the invention together with improved features of structural detail and desirable combinations of parts will be described at length in the following specification and more particularly pointed out in the claims,

55 reference being had to the annexed drawings

for a disclosure of a preferred form of the invention and in which:—

Fig. 1 is a plan view of the lower portion of the head of a bed lasting machine of usual form showing the wipers and the means for operating them;

Fig. 2 is an enlarged detail in plan of the outer end of the supporting member upon which the wipers are carried, the parts being illustrated with the wiper-securing means in locked position;

Fig. 3 is a view similar to Fig. 2 showing the wiper-securing means as retracted to permit removal of the wipers;

Fig. 4 is a vertical section of the wiper supporting member on the line *a—a*, Fig. 2, showing the wipers mounted thereon, and the securing means in locked position;

Fig. 5 is a perspective view of a slidable

pin forming a part of the securing means.

Referring to Fig. 1, the numeral 1 indicates the lower plate of the lasting head, such plate forming the supporting means for wipers and the mechanism for operating the same. As herein shown, the wipers

80 are operated by mechanism of usual and well known form such as is clearly illustrated for example in the patent to Morey, 469,972, March 1, 1892, to which reference may be had for a full disclosure of this

85 portion of the mechanism, which will be briefly described as follows:

2 and 3 are opposed curved slots formed in the surface of the plate 1 and serving to guide a pair of curved link bars 4, 5

90 which lie within the grooves and whose upper surfaces are substantially flush with the surface of Plate 1. 6 is a member slidably guided in a deep groove 7 in the Plate 1, said member 6 having a pin 8 projecting

95 therefrom forming a pivotal connection between member 6 and a lever member 9 which is pivoted to the Plate 1 as indicated at 10, the lever 9 having a handle at 11 by which it may be swung about its pivot. 12 is

100 a slide member superposed on the member 6, and constituting a support for the wipers, as will be hereinafter described. 13, 14

105 are a pair of links pivotally secured to the rear end of the slide member 6, and having their opposite extremities secured pivotally to the rear extremities of the link bars 4, 5, respectively.

15, 16 are a pair of links connecting the rear end of the slide 12 with the respective

links 13, 14. As clearly disclosed in the aforementioned patent, upon swinging movement of the lever 9 the slides 6 and 12 and the links 4 and 5 have imparted to them the proper motions for operating the wipers in the desired manner.

The wiper plates *a*, *b* herein illustrated are of the type disclosed in the patent to Willard, 561,189, June 2, 1896, being pivotally connected at their inner extremities and being provided with open-ended slots 17, 18 adapted for engagement by pins 19, 20 carried at the outer extremities of the respective links 4 and 5.

In accordance with the present invention, means is provided for removably securing the wipers to the supporting slide 12, and reference may be had to Figs. 2, 3, 4 and 5 which clearly disclose the details of this securing means. Referring more particularly to Fig. 4, it will be noted that the wiper plates *a* and *b* are pivotally connected by means of pin or stud 21 which is formed with a shoulder at 22 bearing on the upper surface of plate *b* and is riveted over at 23 to fix it firmly in plate *a*. The plates *a* and *b* are thus secured together, but with freedom to turn relatively about the axis of pivot pin 21. The pivot pin is provided with an enlarged cylindrical portion 24 extending upwardly from the plate *b* and formed at its upper extremity with a head 25, the cylindrical portion of said pin being also furnished with a circumferential groove 26 as shown at 26. The outer extremity of the supporting plate 12 is formed with an open-ended slot or recess 27, the inner end of which is substantially semi-circular and conforms to the cylindrical portion 24 of the pin 21, which may thus be snugly seated in the bottom of the slot 27.

The member 12 is provided near its outer extremity with transverse guideways or bearings 28, 28^a serving to guide a retaining pin 29, the shape of which is clearly disclosed in Fig. 5. This pin is substantially cylindrical in form, but throughout a portion of its extent is slabbed off to provide a flat surface 30, this surface terminating in a shoulder 31 at one extremity. 32 is a groove formed near the opposite extremity of said slabbed-off portion of the pin and extending at right angles to the surface 30. 33 is a lever arm provided with a finger-engaging member 34, said lever arm being fixed to or integral with the pin 29 and extending in a direction parallel to the surface 30.

The pin 29 is normally located within the guideways 28, 28^a and when so placed a stud 35 which extends vertically downward through support 12 and transversely of the bearing 28^a engages the surface 30 of the pin 29, forming an abutment engageable with the shoulder 31 of the pin to prevent the complete removal of the pin from the

bearing 28^a. It will also be noted that when the pin 35 is in engagement with the surface 30, the pin 29 is secured against angular movement.

In the employment of the parts above described, the pin 29 being in withdrawn position as shown in Fig. 3, the projecting portion 24 of the stud 21 which forms the pivot for the wiper members, may be seated within the recess 27 with the head 25 thereof bearing upon the upper surface of the support 12 and the rear portions of the wipers underlying said support. The retaining pin 29 is now slidably moved along the bearing 28^a, (being received within the circumferential groove 26 of the stud 21) until its extremity is seated within the bearing 28. When the pin has been carried into this position the slot 32 will have been brought opposite the pin 35, whereupon the pin may be rotated on its axis by means of the lever arm 33 until the slabbed-off portion 30 of the pin 29 is in the position shown in Fig. 4. In this position the pin 35 lies within the slot 32 and thus prevents any sliding movement outwardly of the pin 29. In this position of the parts the wiper members are securely retained in position on the support 12, while at the same time the securing pin 29 is locked against accidental disengagement.

When it is desired to remove the wipers for substitution of others, it is merely necessary to rotate the pin 29 by means of lever 33 until pin or stud 35 is free from slot 32 thereupon the pin may be slidably retracted to the position shown in Fig. 3 and the wipers removed bodily by disengagement of the stud 21 from the recess 27, the studs 19, 20 at the same time sliding freely from the open-ends of the slots 17, 18 of the wipers. As will be noted, when the locking pin occupies the position shown in Fig. 3, it is impossible for it to become displaced by turning on its axis so that it is ready to be returned to normal position. While as herein shown the stud 21 extends upwardly from the upper wiper only, it is contemplated as within the scope of this invention that under some circumstances such stud might be directed downwardly from the lower wiper or that portions of the stud might extend both upwardly and downwardly for engagement with the support.

Furthermore, while as herein disclosed the securing stud forms the pivotal connection between the wipers of a pair, it is considered to be fully within the scope of the invention to provide separate wiper plates with independent studs in position to be secured upon the proper supporting elements by devices such as herein disclosed.

Having thus now described the invention and a preferred embodiment thereof, together with details of construction and the

mode of operation thereof, what I claim and desire to secure by Letters Patent of the United States is,—

1. In a lasting machine, in combination, a support having an open-ended slot therein, a wiper plate provided with a member engageable with said slot, and manually operable means for retaining said member in position within said slot.
- 10 2. In a machine of the class described, in combination, a support having an open-ended slot therein, a wiper plate, a member projecting from said wiper plate and arranged to be seated in said slot, and a movable gate member for normally closing the open end of said slot.
- 20 3. In a bed lasting machine, in combination, a support provided with a slot having an open end, a wiper plate, a headed stud projecting from the face of said wiper plate and arranged to be seated in said slot, and a pin slidably mounted in said support and normally extending transversely across the open end of said slot.
- 25 4. In a machine of the class described, in combination, a wiper plate, a support therefor, means for removably securing said wiper plate to said support comprising a pin mounted in said support for both axial sliding and angular rocking, and means for locking said pin against sliding movement when in normal position and against angular rocking when in retracted position.
- 35 5. In a machine of the class described, a support, a wiper plate having an element for engagement with said support and means for normally retaining said element in operative engagement with said support comprising a pin slidably mounted in guideways in said support, said pin having a substantially flat longitudinal face extending throughout a portion of its length, and an abutment member engaging said flat face and serving to prevent complete withdrawal
- 40 45 of said pin from its guideways.
6. A lasting machine having, in combination, a support, a wiper plate having a member projecting therefrom and engageable in a slot in said support, and means for normally retaining said member in said slot comprising a pin slidable transversely of said slot, said pin being slabbed-off throughout a portion of its surface to form a substantially flat face, and a fixed stud engaging said flat face to prevent removal of the pin from the support, said pin having formed therein a transverse groove near one extremity and substantially at right angles to said face, said groove when brought opposite said stud permitting angular rocking of said pin.
7. In a lasting machine, in combination, a support, a pair of wiper plates, and a pin fixed in one of said plates and forming a pivotal support for the other plate, said pin having a headed portion extending outwardly from said plates and arranged for removably engaging said support.
8. In a lasting machine, in combination, a support having an open-ended slot therein, a pair of wiper plates, a pin pivotally connecting said wiper plates, said pin having a shank portion projecting beyond the surface of one of said plates and having an enlarged head thereon spaced from said plate, said shank portion being arranged to be seated in said slot, and means for removably securing said pin within said slot.
9. In a machine of the class described, a support having a slot therein, a pair of wiper plates, a pin pivotally connecting said plates and having a lateral extension provided with a peripheral groove and arranged to extend within said slot, and a pin carried by said support and engageable in said groove to retain said pin in said slot.
10. In a machine of the class described, a wiper plate, a support, and means slidable to retain and release said plate and support in and from assembled relation and rockable when in retaining position to be locked from sliding to releasing position.

In testimony whereof, I have signed my name to this specification.

CHARLES F. ADAMS.
